Primary Examiner—Philip S. Hyder
Attorney, Agent, or Firm—Grace J. Fishel**[57] CLAIM**

The ornamental design for a sample case, as shown.

DESCRIPTION

FIG. 1 is a perspective view of a sample case showing my new design, the flap being shown in an open position; FIG. 2 is an top view thereof shown with the flap in a closed position;

FIG. 3 is a bottom view thereof shown with the flap in a closed position;

FIG. 4 is a right side elevation as viewed in FIG. 1 shown with the flap in a closed position;

FIG. 5 is a front view thereof shown with the flap in a closed position;

FIG. 6 is a left side elevation view thereof shown with the flap in a closed position; and,

FIG. 7 is a rear view thereof shown with the flap in a closed position.

The sample case is shown fragmentarily to indicate an indeterminate length.
